UNITED STATES PATENT OFFICE.

GEORGE R. ELLIOTT, OF ECORSE, MICHIGAN.

MOLD FOR CONCRETE CHANNELS AND FLOORS.

1,407,737.

Specification of Letters Patent. Patented Feb. 28, 1922.

Application filed September 27, 1919, Serial No. 326,814. Renewed October 10, 1921. Serial No. 506,853.

To all whom it may concern:

Be it known that I, GEORGE R. ELLIOTT, a citizen of the United States of America, residing at Ecorse, in the county of Wayne 5 and State of Michigan, have invented certain new and useful Improvements in Molds for Concrete Channels and Floors, of which the following is a specification, reference being had therein to the accompanying drawings.

This invention relates to molds for concrete channels and floors and the object is primarily to render both the outer walls and the core piece of the molds, adjustable 15 so as to facilitate removal of the channels or floor members when the same are set.

A further object is to effect the desired adjustability of the core piece by a mechanism automatically actuatable for engagement 20 with the mold supporting surface whereby the core piece will be made to assume its proper shape for pouring of the channel merely by disposing the mold in its normal position.

25 A preferred embodiment of the invention is hereinafter described and is illustrated in the accompanying drawings, wherein:

Figure 1 is a plan view of the mold;

Figure 2 is a bottom view of the same;

30 Figure 3 is a view of the mold in cross section;

Figure 4 is a view similar to Figure 3, disclosing an alternative form of the invention.

35 Figure 5 is a sectional elevation of the mold, the section being taken upon line 5—5 of Figure 1;

Figure 6 is a view similar to Figures 3 and 4 showing a provision for casting a 40 floor in situ by means of the disclosed construction.

The mold in the form shown in Figures 1, 2, and 3 has a core piece disposed between the same. Each side frame comprises a 45 board or plate 1 forming a side wall of the mold, a bottom board or plate 2, and a series of spaced brace members 3 arranged transversely to the members 1 and 2 and rigidly connecting the same. Said side 50 frames are hinged, as indicated at 4, to elongated strips 5 forming bottoms of the mold chamber.

The core piece comprises a pair of complementary arch-forming members 6, spaced 55 slightly at the center of the arch, as indicated at 6^a, brace plates 7 for said mem-

bers, arranged transversely thereof within the arch, and a sheet metal facing 8 for the core piece, said facing covering the members 6 and spanning the space between said members. The strips 5 are connected by spaced pairs of bars 9, the bars of each pair being hinged respectively to the strips 5 as indicated at 10 and being hinged to each other at 11 beneath the center of the arch formed by the members 6. Normally the bars 9, the strips 5, and the members 2 are maintained in the same plane by the surface 11^a upon which the mold rests, as is indicated in full lines in Figure 3. The 70 ends of the core piece are slightly inclined to the vertical and are closed by loose boards or plates 12. The ends of the mold proper are closed by loose boards or plates 13, which are adapted to bear terminally 75 against vertical cleats 14 secured in opposed relation to the side walls to resist the thrust exerted by the plastic concrete.

In the use of the described construction, when a block is being poured, engagement 80 of the members 2 of the side frames with the surface 11^a supporting the mold maintains the mold side walls 1 vertical, and engagement of said surface with the bars 9 maintains the same in alignment with each 85 other so that the arch-forming members 6 occupy their proper relative positions shown in full lines in Figure 3. When the channel is to be removed from the mold, the latter may be either arranged on edge, that is to 90 say with one of the side frames acting as a support, or may be completely inverted. This permits either one or both of these frames to be swung upon the hinge 4 to the dash line position shown in Figure 3, 95 and allows the bars 9 to be shifted to the angular relation similarly indicated in said figure. The two halves of the core member are thus subjected to a slight swinging movement toward each other permitted by 100 flexing of that portion of the sheet metal 8 spanning the space interval 6^a between the members 6, the shifted position of said halves being also shown in dash lines in Figure 3. The core piece thus acquires a 105 slight clearance from the block whereby the latter may be removed from the mold without binding or danger of breakage. After removal of the block, the side frames comprised by the parts 1, 2 and 3 are returned 110 to their normal positions and the mold is again disposed in pouring position upon the

floor or other supporting surface, the latter effecting the shifting of the bars 9 into alignment and a consequent return of the halves of the core piece to their normal relation.

In the construction which is disclosed in Figure 4, there is employed the same core piece as has been already described, but the parts forming the sides of the mold are entirely separate from said core piece. Each of said sides, in this instance, is formed by a pair of angle bars 15 and 16 set back to back, the vertical flange of the bar 15 forming an outer wall of the mold, and the horizontal flange thereof projecting slightly beneath the adjacent half of the core piece and supporting the same, and forming at the same time a bottom for the mold chamber.

What I claim as my invention is:

20 1. A core piece for concrete channel molds, comprising a pair of complementary arch-forming members, a flexible connection between said members at the top of the arch, and an adjusting means for said members formed by a pair of bars having opposed ends respectively pivotally connected to the arch-forming members and adjacent ends pivotally engaging each other, said bars being normally aligned to maintain the arch

25 forming members adjusted for pouring, and being angularly adjustable to swing the arch-forming members toward each other.

2. A core piece for concrete channel molds, comprising a pair of complementary arch-forming members, a sheet metal facing for said members, establishing a flexible connection between the same at the top of the arch, and means for angularly adjusting the arch-forming members about an axis established by said flexible connection.

3. A core piece for concrete channel molds, comprising a pair of complementary arch-forming members, a facing for said members, establishing a flexible connection between the same at the top of the arch, and a pair of bars arranged transversely of the core piece at the bottom thereof, pivotally

connected at their adjacent ends, and having their opposed ends respectively pivotally attached to the arch forming members.

50

4. A core piece for concrete channel molds, comprising a pair of complementary arch-forming members, means establishing a flexible connection between said members at the top of the arch, members forming a bottom to the mold chamber, secured respectively to the arch-forming members at the feet of the arch, and mechanism engaging said bottom forming members for swinging the arch-forming members toward each other about said flexible connection.

5. The combination with an arched core piece for concrete channel molds, the sides of which core piece are adjustable toward each other to establish a clearance from the molded channel, to facilitate the removal of the same, of a pair of bars arranged transversely of the core piece at the bottom thereof, pivotally connected at their adjacent ends and pivotally engaging the sides of the core piece at their opposed ends, the adjacent ends of said bars being downwardly adjustable to an angular relation to establish a clearance, and being upwardly adjustable to an aligned relation through engagement with the surface supporting the core piece.

6. A concrete channel mold, comprising a core piece, members secured to opposite sides of the core piece forming the bottom of the mold chamber, and side pieces for the mold chamber respectively pivotally connected to said bottom forming members.

7. A concrete channel mold, comprising a pair of complementary arch members forming a core piece, means flexibly connecting said members at the top of the arch, mechanism for swinging said members about said flexible connection to establish a clearance from the molded channel, and side pieces for the mold pivotally connected to the core piece.

In testimony whereof I affix my signature.

GEORGE R. ELLIOTT.
